BOOKCASE

Henry S. Akola, Glendale, Calif. (½ John E. Wagner, 1041 E. Green St., Suite 202, Pasadena, Calif. 91101)

Filed Aug. 13, 1970, Ser. No. 44,482

Term of patent 14 years

Int. Cl. D6—04

U.S. Cl. D6—186

FIG. 1 is a front elevational view of a bookcase in accordance with the design of this invention;

FIG. 2 is a left side elevational view thereof, the right side being a mirror image of the left side; and

FIG. 3 is a front perspective view of the design of FIG. 1.

The back of the bookcase is plain and unornamented.
I claim:

The ornamental design for a bookcase, as shown and described.
